UNITED STATES PATENT OFFICE.

HERMAN COHN, OF NEW YORK, N. Y.

MACHINE FOR PRESSING AND FORMING HATS.

1,257,675.

Specification of Letters Patent. Patented Feb. 26, 1918.

Application filed June 25, 1917. Serial No. 176,807.

To all whom it may concern:

Be it known that I, HERMAN COHN, a citizen of the United States, residing at New York, in the county of New York and State 5 of New York, have invented certain new and useful Improvements in Machines for Pressing and Forming Hats, of which the following is a specification.

My invention relates to machines for 10 pressing and cutting out hats made of fabric, such as velvet or the like, in which it is customary to first press and shape the brim of the hat from a suitable blank or piece of material and then cut out a space in the center of the hat for attaching the crown there-of, which is made of a separate piece of material. It is customary to leave a flange of 15 about an inch in height around the central opening of the piece of material, so as to 20 enable the sewing on of the crown of the hat.

It has heretofore been customary in pressing and shaping the brim of the hat, to provide two pressing dies, one above the other, 25 which were suitably heated so as to facilitate the pressing of the material. These dies had their adjacent surfaces of the shape of the brim of the hat and the lower die had at or near its center, a depression of about 30 an inch in height, this depression corresponding to the shape of the opening for receiving the crown of the hat. Instead of providing a depression in the lower die, it could also be cut away at this point so as to 35 leave an opening in its surface corresponding to the opening for receiving the crown of the hat. The upper die had, at its bottom, a projection corresponding in shape to the depression or opening in the lower die.

40 In the operation of this device, two workmen would take an unperforated piece of material of sufficient area to provide for the brim of the hat and they would hold it at the top of the lower die. Then the upper die 45 would be caused to descend upon the material held on the lower die, by any suitable means, such as a foot press or the like. The upper die would press the material on the lower die, thus shaping it, and it would also 50 force the material above the depression or opening in the lower die, into this depression or opening. When the upper die was removed, the line where the material had been forced into the depression or opening in the 55 lower die, could be seen by the operator,

because the heating and pressing left a mark at that point.

After this was done, the operator would cut away the center of the pressed piece of material, leaving a flange of about an inch 60 to receive the crown of the hat which was then sewed on.

This method has led to a waste of material in that the upper die would always force the fabric into the opening or depression in the 65 lower die, so that instead of using a piece of material of the exact size of the brim of the hat, it was always necessary to allow for at least an inch more all around the brim of the hat. This has been a considerable 70 item of loss in working with expensive velvets, especially since hundreds of hats are usually made by a single manufacturer. In addition, the operation of this device was not always reliable because the men who 75 were feeding the material to the dies had to hold it against the pull that was exerted by the upper dies forcing the material into the opening of the lower die.

The object of my invention is to provide 80 a new and improved construction of pressing and shaping dies that shall be uniform and reliable in operation, economical of material, shape and press the hat more effectively, and permit the operators to see at all times 85 the condition of the material.

Other objects of my invention are to provide a simple and efficient construction for carrying out the above mentioned purposes, and these objects shall be set forth in the 90 following description and drawings which illustrate a preferred embodiment of my invention.

Figure 1 is a front elevation of my improved construction, the pressing dies being 95 shown in the position suitable for pressing the material.

Fig. 2 is a side elevation of the construction of Fig. 1.

Fig. 3 is a top view of Fig. 1.

Fig. 4 is a perspective view of the supplemental cutting die, seen from below, and showing the tapering cutting knives, which are widest at their outer ends, so that their outer ends act as piercing points.

Fig. 5 is a detail view showing the cutting of the fabric.

The framework of my improved construction consists of two triangular frame-pieces 1, connected by a horizontal bar 3 and hav-

100

105

110

ing other horizontal members connected thereto, such as a table 24. To the cross-bar 3 a lever 4 is pivoted which can be downwardly actuated by the foot and held downwardly by member 5, and which is upwardly urged by the springs 6, fastened to the cross-bar 8 at their upper ends, and fastened at their lower ends to a short cross-bar 7 connected to the lever 4.

10 A vertical jointed link 9 is pivoted to the lever 4 at 10. At its upper end, the link 9 carries a fork 38 to which vertical rods 12 are connected by means of the yoke 13. These vertical rods 12 slide up and down 15 in suitable guides provided in the table 24 and at the top of the frame-pieces, so that they always move in a vertical direction.

The vertical rods 12 are threaded at their 20 upper ends where they are adjustably connected to a frame 16 by means of nuts 30 and 31. By suitably rotating these nuts 30 and 31, the frames 16 can be adjustably held on the rods 12. The frame 16 has connected thereto threaded vertical supporting 25 rods 17 which are adjustably connected thereto by means of the nuts 28.

The vertical supporting rods 17, carry at 30 their lower ends an upper pressing die 15 which is of the exact shape of the portion 35 of the brim of the hat, and has an opening in the center of the exact shape of the portion of the brim to which the crown is to be attached.

Hence, by suitably moving the lever 4 35 down, the upper die 15, which may be heated if desired, by any suitable means, and which may be called the upper pressing die, can be downwardly moved, as shown in Figs. 1 and 2 and by releasing the lever 4, the 40 springs 6 urge the upper die 15 upwardly.

Connected to the table 24 is a stand 32 to which another table 25 is connected. The lower pressing die 14 is detachably connected to the table 25 by the fastening members 26. The lower pressing die 14 is of substantially the exact shape of the brim of the hat and of the upper pressing die 15, there being just enough difference of taper 45 between the adjacent surfaces of dies 14 and 15, which generally speaking, are of frustoconical shape, to stretch the fabric over the lower die 14, without injuring it, when the dies are pressed together. This difference of taper or contour uniformly stretches the 50 fabric outwardly, or radially from the center of the dies, as well as downwardly. Of course, the adjacent surfaces of the dies could have the same contour. When the upper die first contacts with the fabric, 55 since this fabric has a certain thickness, the upper die will not, at the moment of the said contact, coincide with the adjacent surface of the lower die, if these dies are properly dimensioned. The upper die will 60 move downwardly and also carry the fabric

with it, thus stretching it, until the movement of the upper die is stopped. If sufficient pressure is applied, the dies themselves will slightly yield, which would assist this action. The hollow frame 16 has two cross-members 27 connected thereto. At the center of these two cross-members 27 is a threaded opening into which a vertical screw 18 is fitted. This screw 18, which is rotated by means of the hand-wheel 19 has fastened thereto, at its lower end, a carrier 22, whose periphery is of such shape that it fits into the opening in the upper die 15.

At its underside the carrier 22 has four 75 detachable blades 23 fastened thereto, by any 80 suitable fastening means 29.

The operation of my improved device is as follows:—

Two operators place a piece of velvet on the lower die 14 and one of them depresses 85 the lever 4 thus bringing the upper die 15, down upon the lower die 14. The carrier 22 and the blades 23 are carried down with the frame 16, but the screw 18 has been raised sufficiently so that the tapering knives 90 or blades 23 and the carrier 22 do not touch the fabric. By this operation the fabric is tightly stretched over the lower die 14, and the central part thereof, which is to be cut away to leave an opening for sewing on the 95 brim of the hat, is tightly stretched over the opening in the lower die 14. As a result a minimum amount of material is present between the dies 14 and 15 and there is no drawing in of the material for an inch or 100 more, which took place under the old construction of the dies, in which the flange for the sewing-on of the crown was shaped simultaneously with the pressing of the brim.

105 While the upper die 15 is thus pressed against the lower die 14, it irons the brim as one or both of these dies are suitably heated by any well-known means, not shown in the drawings, and which in themselves 110 form no part of my invention. The ironing is accomplished upon the tightly and uniformly stretched fabric so that a superior effect is secured.

Now the operator rotates the hand-wheel 115 19 and lowers the carrier 22 which is guided by the rods 21, so that the knives or blades 23, contact with the material within the opening of the die 15 and neatly cut it along two lines at right angles to each other 120 and thereby release the tension on this portion of the fabric. The carrier 22 now enters into an opening of the upper die 15, and serves as a supplemental die, to iron out a flange for sewing on the crown of the 125 hat.

Fig. 5 shows how the material has the two slits cut therein. The superfluous portions of the four angular pieces of material thus formed are trimmed away by hand.

- I have described a preferred embodiment of my invention but it is clear that numerous changes and modifications could be made without departing from its spirit.
- 5 Some of the parts might be caused to move automatically and some of the details might be omitted, without departing from the essence of my invention as defined in the following claims.
- 10 1. In a machine for forming the brims of hats, the combination of an upper annular die and a lower annular die, the said dies having superposed alined surfaces of substantially ring-like, frusto-conical shape, and 15 means for bringing together and separating the said dies, the adjacent surfaces of the said dies being so dimensioned and alined, that when they are brought together they downwardly and radially stretch and press 20 the piece of material placed between them, and only operate on that portion of said piece between the ring-like operating surfaces of the said dies.
2. In a machine for forming the brims of 25 hats, an upper annular die and a lower annular die, the adjacent surfaces of said dies being of different contour, so as to downwardly and radially stretch a piece of material between them when they are forced 30 together, an independently movable supplemental die adapted to fit into the opening of said upper annular die, means for bringing together the said annular dies and means for then moving the said supplemental die 35 toward the said annular dies.
3. In a machine for forming the brims of hats, an upper annular die, a lower annular die, an independently movable supplemental die adapted to fit into the opening of said 40 upper annular die, means for bringing together and separating said dies, and cutting means adapted to operate in the opening of said upper die before said supplemental die enters said opening.
- 45 4. In a machine for forming the brims of hats, an upper annular die, a lower annular die, an independently movable supplemental die adapted to fit into the opening of said upper die, means for bringing together and 50 separating said dies, and means adapted to first pierce and then cut the fabric within the said opening of said upper die, before said supplemental die enters said opening.
5. In a machine for forming the brims of 55 hats, an upper annular die, a lower annular die, an independently movable supplemental die having cutting knives at its under side and adapted to fit into the opening of said upper die, and means for bringing together and separating said dies. 60
6. In a machine for forming the brims of hats, an upper annular die, a lower annular die, an independently movable supplemental die adapted to fit into the opening of said upper die, having four cutting knives 65 at its under side, said knives having piercing points at their outer ends and being arranged at right angles to each other, and means for bringing together and separating said dies. 70
7. In a machine for forming the brims of hats, an upper annular die, a lower annular die, an independently movable supplemental die adapted to fit into the opening of said upper annular die, and having cutting 75 knives at its under side, the cutting edges of said knives tapering downwardly from their inner to their outer ends, and means for bringing together and separating said dies.
8. In a machine for forming the brim of 80 a hat, pressing dies having their adjacent surfaces of different contour so as to downwardly and radially stretch the peripheral portion of said brim, and a supplemental and independently movable pressing die 85 adapted to thereafter press and form the crown portion of said brim.
9. In combination, a frame, cross-members in said frame having a threaded opening at 90 their center, a screw fitting into said opening, a wheel for rotating said screw, an upper annular die carried by said frame, a second annular die adapted to coöperate with said first-mentioned die to clamp a piece of fabric, the adjacent surfaces of said 95 dies being of slightly different inclination to the vertical in order to stretch the fabric clamped between them, a supplemental die adapted to fit into the opening in said upper die and having on its under side four 100 knives of the same dimensions radiating from the center of said supplemental die, said knives being at right angles to each other and having their cutting surfaces tapering downwardly and outwardly from the 105 center of said supplemental die and means for raising and lowering said frame.

In testimony whereof I hereunto affix my signature.

HERMAN COHN.
